HOSIERY

John Lee Lesher, Williamstown, Pa., assignor to
 Unrivaled Hosiery Mill, Inc., Williamstown,
 Pa., a corporation of Pennsylvania

Application November 16, 1939, Serial No. 304,648

5 Claims. (Cl. 66—172)

This invention relates to hosiery and has for an object to provide an improved top for the same whereby the hosiery will be self-supporting on the leg of the wearer.

5 A further object of this invention is to incorporate elastic thread into certain areas of the top of plain knit hosiery so that the same will be self-supporting on the leg of the wearer and so that the elastic will not be unduly binding 10 when the hosiery is being worn or when it is being put on or taken off the leg.

Other advantages and objects of the invention will become apparent from the following description of the drawing in which:

15 Figure 1 is a side view of a stocking embodying the invention.

Figure 2 is a view of the upper part of a stocking showing a modification of the invention.

20 Figure 3 is a view of the upper part of a stocking showing another modification of the invention.

Figure 4 is a detail stitch view of a manner of incorporating the elastic yarn in the body fabric, and

25 Figure 5 is a detail view in cross section of a rib formed by means of the incorporation of the elastic yarn in the body fabric.

This invention is applicable to hosiery of the type adapted to be worn with the upper end 30 thereof below the knee of the wearer whether it extend above or below the calf of the leg. It is the purpose to provide such hosiery with self-supporting means with the use of the minimum amount of elastic yarn in the hosiery for such 35 purpose. The use of more than the minimum amount of elastic yarn than is required to make the hose self-supporting is objectionable as it unduly binds the leg and makes it difficult to put on and take off, especially over the heel.

40 In Figure 1 is shown a stocking 6 having the usual foot 7, leg 8 and the top of plain fabric modified according to my invention. The top is of the usual length and has an imitation rib section 9 in the front and a plain section 10 in the back, an elastic yarn being incorporated in the 45 section or panel 9 but not in the panel 10. As shown at 11 at the upper end of the stocking, the elastic is continuous around the entire circumference for one or more courses to give an 50 elastic effect to the upper end of the stocking to provide a good appearance and to aid the stocking in being self-supporting. The one or more complete courses 11 of elastic also provide a beginning selvage edge construction for the fabric. The panel 9 occupies substantially one-half

of the entire number of plain wales, although being constricted, the appearance is that the panel 9 is of lesser circumferential extent than the panel 10. It is within the scope of this invention to extend or reduce the number of wales within the panel 9 so long as the top is self-supporting.

The Figures 2 and 3 illustrate modifications of the invention, in the stocking 12 the imitation rib panel 13 is at the rear half of the stocking top and the plain panel 14 is at the front, with the complete circumferentially extending courses at the upper end of the top being shown at 15. In the stocking 16, the imitation rib panel sections 18, 18, 18 are spaced apart from each other vertically by the plain intermediate panel sections 19, 19 in one-half of the top, and the imitation rib panel sections 17, 17 are spaced apart from each other vertically by the plain intermediate panel section 19 in the other half of the top, the 20 panel sections 17 and 18 being staggered with relation to each other, each section 17 and 18 being opposite a section 19. The complete circumferentially extending courses at the upper end of the top being shown at 20. Each of the sections 17 and 18 extend preferably half way around the top, but may extend for less or more than this distance and in the latter event will embrace a certain number of wales in common 25 in the overlapping areas.

30 Figure 4 is illustrative of one manner of incorporating the elastic yarn 22 in the rear face of the plain fabric made of the yarn 21. In the knitting on a circular machine certain recurrent needles only take the elastic yarn in their hooks 35 at a point in advance of the regular knitting station, the elastic yarn floating in back of the intervening needles. At the regular knitting station all the needles rise to take the main yarn 21 and in doing so cause the loops, and the 40 lengths of elastic on the recurrent needles, to be positioned below the opened latches. Upon knitting the main yarn 21, the recurrent needles cause the elastic to be cast off unknit and caught in the fabric as shown at 23, 23 in the wales 45 24, 24, thus securely incorporating the elastic. Instead of thus incorporating the elastic yarn, it may be actually knit in with the body yarn as a plated stitch or as a separate stitch, the particular manner of incorporating the elastic being 50 immaterial.

The fabric in Figure 4 is stretched flat with the elastic yarn and the plain fabric lying side by side, however, in Figure 5 which is a section of Figure 4 on lines 5—5, the fabric is shown in the

natural shape it assumes when the elastic yarn is permitted to contract to its natural state. It will be seen that the wales between the wales in which the elastic is caught, extend outwardly to give a rib effect to the top. In this instance the elastic is caught in every fifth wale and every fourth course, but obviously this may be varied as desired so long as the rib effect is retained in the fabric.

10 In the circular knitting machine in making the panel effect of the imitation rib as shown in Figures 1, 2 and 3, the operation of the machine is adjusted so that the elastic yarn is first incorporated into the complete course or courses at 15 11, 15 or 20 by action of the complete circle of needles and thereafter the elastic is taken by the series of recurrent needles in the appropriate one-half of the needle circle, the needles in the other half of the needle circle taking the body 20 yarn only. Thus the elastic yarn, in the panel sections, is taken by the recurrent needles in one-half the needle circle and is floated in each course across the needle circle from the first to the last of the recurrent needles. The leg and 25 foot of the stocking is made in the usual manner and upon removal from the machine the floats of the elastic yarn are preferably cut out and discarded. In order to insure that the ends of the elastic in the panels will not pull out or 30 creep coursewise, the end needle or needles taking the elastic yarn may knit the same into the body fabric.

It has been found that with the elastic panel sections extending substantially half way around the top, that it is easier, due to the non-contracted plain knit section such as 10 and the absence of complete courses of elastic, to pull the stocking over the heel of the foot of the wearer. Also that in position on the leg, the elastic panel 35 is sufficient to cause the stocking to be self-supporting without causing the courses of the elastic yarn 22 to bind the leg, stop the circulation of blood, or cause objectionable marks on the flesh of the leg. When the elastic yarn courses extend completely around and throughout the top, it is the elastic which is held in place, whereas with the elastic yarn in panels it acts as a take-up in the plain fabric, causing the latter to be drawn taut around the leg and this in addition 40 to the presence of the horizontal floats of the

elastic 22 on the inside of the elastic panels, makes the hose self-supporting.

I claim:

1. In an article of hosiery, a leg portion comprising a body having a top, said top being plain 5 knit of inelastic fabric thread and having an elastic thread incorporated at the upper end of said top for one or more complete courses and incorporated in partial courses only of other courses of said top to provide an imitation rib effect in 10 the portion of the top comprising said partial courses, said portion comprising a substantially wale-wise extending area.

2. In an article of hosiery, a foot portion, a leg portion comprising a body having a top, said top 15 being plain knit of inelastic fabric thread and having an elastic thread incorporated at the upper end of said top for one or more complete courses and incorporated in substantially half courses only of other courses of said top to provide 20 an imitation rib effect in the half portion of the top comprising said half courses.

3. In an article of hosiery, a foot portion, a leg portion comprising a body portion having a top, said top being plain knit of inelastic fabric 25 thread and having an elastic thread incorporated at the upper end of said top for one or more complete courses and incorporated in the front half only in the remainder of said top to provide an imitation rib effect therein.

4. In an article of hosiery, a foot portion, a leg portion comprising a body portion having a top, said top being plain knit of inelastic fabric thread and having an elastic thread incorporated at the upper end of said top for one or more complete 35 courses and incorporated in the rear half only in the remainder of said top to provide an imitation rib effect therein.

5. In an article of hosiery, a foot portion, a leg portion comprising a body portion having a top, said top being plain knit of inelastic fabric 40 thread and having an elastic thread incorporated at the upper end of said top for one or more complete courses and incorporated in each of a plurality of separate sections to provide an imitation rib effect in each section, each of said sections extending for a number of courses, the sections being staggered with relation to each other 45 in said top.

JOHN LEE LESHER. 50
